ADVERTISING SIGN FOR BUSES OR THE LIKE

Irving R. Yarber, 3158 Goddard Road, Toledo, Ohio

Filed Oct. 16, 1961, Ser. No. 67,102

Term of patent 14 years

(Cl. D1—12)

FIG. 1 is a front view in elevation of an advertising sign for buses or the like embodying my new invention;

FIG. 2 is an end view in elevation of the sign shown in FIG. 1;

FIG. 3 is a front perspective view on an enlarged scale taken from above and at one end of the sign shown in FIGS. 1 and 2;

FIG. 4 is a vertical sectional view taken along the line 4—4 of FIG. 3.

The broken line representation of the bus in FIGS. 1 and 2 and of the additional sign in FIG. 2 are for purposes of illustration only.

My invention resides in the portion of the drawing shown in solid lines.

I claim:

The ornamental design for an advertising sign for buses or the like, as shown and described.
